ATTORNEY.

UNITED STATES PATENT OFFICE

RICHARD G. WEDEMANN, OF MILWAUKEE, WISCONSIN

COLLAPSIBLE UMBRELLA

Application filed February 19, 1930, Serial No. 429,743, and in Germany September 21, 1929.

This invention relates to improvements in collapsible umbrellas.

It is an object of this invention to provide an umbrella which may be folded into a compact unit and stored in the umbrella handle.

Another object is to provide ribbing and a cover therefor which may be folded back upon the outer surface of the cover.

A still further object is to provide a telescopic rod for the umbrella slidable into the handle and about which the ribbing and cover may be nested before sliding into the handle.

Other novel features will appear as the description of the drawing progresses and in

Fig. 1 is a view in side elevation showing the umbrella ready for use, a portion of the ribbing and covering being removed to show the interior.

Fig. 2 is a view in vertical section showing the umbrella as it appears prior to being placed in the umbrella handle.

Fig. 3 is a sectional view taken on the line 3-3 of Fig. 2.

Fig. 4 is a view of the handle in vertical section showing the umbrella stored therein.

Fig. 5 is a view showing the rib joint.

Fig. 6 is a fragmentary view in vertical section showing a modified handle.

Throughout the several views, like parts are designated by the same reference characters.

The handle 1 is tubular and is preferably made of sheet metal bent into cylindrical form and having its margins welded together at 2 to provide a longitudinal rib interiorly of the handle. Slidably mounted in the handle is a plunger 3 having a slot 4 coacting with the rib 2 to prevent relative rotation between the handle and plunger. The plunger is provided with a latch 5 urged outwardly by a spring 6 and engageable in the aperture 7 in the handle to hold the plunger against sliding movement.

Secured to the plunger 3 is a tubular rod 8 having at its upper end a slot 9. Slidable in the rod 8 is a tube 10 having at its lower end a latch member 11 urged outwardly by the spring 12 and engageable in slot 9 when the tube is moved outwardly of the rod 8.

Intermediate the ends of tube 10 is a second latch member 13 actuated outwardly by spring 14. This member 13 normally extends from tube 10 sufficient distance to engage in slot 15 in the collar 16 which is slidable on rod 8. Collar 16 is bell shaped at its lower margin 17 to provide means for releasing latch member 11 from slot 9 when the collar is moved downwardly on the rod 8. A pin 18 is provided in the tube 10 to engage the upper margin of collar 16 and thereby to limit the latter in its upward movement.

Pivotedly carried by the upper end of the collar 16 is a series of links 19 which are pivotally connected with corresponding umbrella ribs 20. The ribs 20 are each divided into two portions 21 and 22 connected together by hinge member 23 and to which they are respectively pivoted. Hinge members 23 comprise channel pieces and when the rib portions are in extended relation the bottom of the channels serve to hold the rib portions as shown in Fig. 1. As indicated the rib portions 21 are pivotally mounted on the end piece 24 secured to the tube 10. Carried by the piece 24 is a cap 25 which closes the upper end of the handle 1 when the umbrella is positioned therein. A covering 26 is secured to the ribs 20 and, as may be seen from Fig. 2, is disposed between the rib portions when the latter are folded.

To place the umbrella in the handle 1, the collar 16 will be released by pressing the latch 13 inwardly. The collar 16 will then slide along tube 10 and upon tube 8 and in so doing allow the umbrella to collapse. Further movement of the collar will cause the latch 11 to move inwardly and release the tube 10 which may then slide into the rod 8 and simultaneously move the collar to the position shown in Fig. 2. The umbrella will then be gathered about the rod 8 and the latch 5 released. Upon release of the latter latch, the whole structure may then be nested in the handle as shown in Fig. 4.

To remove the umbrella from the handle plunger, rod 8 and tube 10, will be moved to the extended position at which time the umbrella may be opened in the usual manner.

From the foregoing it is apparent that a rather novel collapsible umbrella is provided which is simple in structure and compact when not in use. I recognize, of course, that modifications may be made without departing from the spirit of this invention and I, therefore, do not limit the claims to the specific illustrations.

In Fig. 6 is shown a handle which is provided with a spiral rib 2' engaged in a corresponding groove 4' in the plunger 3. Thus when the umbrella is being inserted in the handle as previously noted, it will be caused to rotate as the plunger moves along the rib 2'. Consequently, the umbrella will be more easily nested in the handle.

I claim:

1. In a collapsible umbrella, a hollow handle having a spiral rib interiorly thereof, and a plunger movable in the handle and having a groove complementary to said rib.
2. In a collapsible umbrella, a hollow handle having a spiral rib interiorly thereof, a plunger movable in the handle and having a groove complementary to said rib and an umbrella cover supporting rod carried by the plunger, the space between said handle and rod being sufficient to receive said cover, whereby rotative movement of the plunger will cause the cover to enter the handle in a spiral path.

RICHARD G. WEDEMANN.
